(57) **CLAIM**

The ornamental design for an optical aiming device mount, as shown and described.

DESCRIPTION

FIG. 1 is a top perspective view of an optical aiming device mount showing my new design;

FIG. 2 is a front side view thereof;

FIG. 3 is a back side view thereof;

FIG. 4 is a left side view thereof;

FIG. 5 is a right side view thereof;

FIG. 6 is a bottom view thereof;

FIG. 7 is a top view thereof;

FIG. 8 is a top perspective view thereof; and,

FIG. 9 is a top perspective view thereof.

The broken line in the drawings depicts unclaimed portions of the optical aiming device mount only and forms no part of the claimed design. The rifle depicted in broken line in FIGS. 8-9 and the brake line thereof discloses unclaimed environmental subject matter only and forms no part of the claimed design.

1 Claim, 8 Drawing Sheets
